METHOD FOR SIZING THE TERMINALS OF
PIPE FITTINGSEugene M. Cartwright, North Woodbury, Conn.,
assignor to Chase Brass & Copper Co. Incorporated,
Waterbury, Conn., a corporation

Application June 22, 1938, Serial No. 215,177

4 Claims. (Cl. 29—157)

This invention relates to an improved method for shaping and sizing the terminals of elbows, T's, and other tubular articles constructed of wrought metal and designed to be telescopically 5 interfitted one with another preliminary to uniting them by means of a sweat-soldering operation.

The primary object of the present invention is to provide an improved method whereby the terminals of wrought-metal tubular articles of the character referred to may be sized and shaped with a high degree of accuracy; whereby the metal composing the terminals may be wrought or worked in such a way as to enhance their 15 hardness and tenacity; and whereby the said terminals may be rendered capable of forming sweat-soldered joints of high quality with inter-fitted pipes, pipe fittings, and the like.

One object of the invention is to provide an 20 improved method whereby certain undesirable conditions and inherent imperfections in the unsized pipe-fitting terminals may be overcome in a simple and effective manner in the finished pipe fitting.

Another object of the invention is to provide 25 an improved method whereby an improved sequence of cold-working operations may be employed on unsized pipe fittings to produce shaped and sized pipe fittings of greatly-improved quality for their intended purposes.

With the above and other objects in view, as will appear to those skilled in the art from the present disclosure, this invention includes all features in the said disclosure which are novel over 35 the prior art and which are not claimed in any separate application.

In the accompanying drawings, in which certain modes of carrying out the present invention are shown for illustrative purposes:

40 Fig. 1 is a diagrammatic front elevation of suitable apparatus for oversizing the terminal of an unsized pipe fitting T by an expanding operation performed on the T;

Fig. 2 is a side elevation of Fig. 1 with one of 45 the separable holder-blocks for holding the T being removed and an unfinished T being shown in position to have one of its terminals expanded to oversize;

Fig. 3 is a view similar to Fig. 2 showing a 50 mandrel of oversized predetermined diameter at the end of its operating stroke;

Fig. 4 is a medial vertical section of the draw-die assembly whereby the oversized terminal pipe fitting T may be sized by a reducing cold-working 55 operation, a sizing mandrel of predetermined

diameter being shown at the commencement of its stroke;

Figure 5 is a view similar to Fig. 4 showing the sizing-mandrel with the attached pipe fitting T at the end of the downward movement of said 5 mandrel;

Fig. 6 is a transverse section on the line 6—6 of Fig. 5;

Fig. 7 is a top plan view of the two-part draw-die assembly;

Fig. 8 is a side elevation of a T-blank partly 10 in section with its oversized terminals indicated by broken lines;

Fig. 9 is a similar view of the finished T;

Fig. 10 is a side elevation of the draw-die 15 assembly for use in connection with a pipe-fitting elbow;

Fig. 11 is a medial longitudinal section of the draw-die assembly shown in Fig. 10;

Fig. 12 is a fragmentary section on the line 20 12—12 of Fig. 11;

Fig. 13 is a side elevation of an elbow with 25 oversized terminals partly in section on one of said terminals and indicated in dotted lines on the other one of said terminals; and

Fig. 14 is a side elevation similar to that shown in Fig. 13 with a fragment of the wall of one terminal broken away to show the modified wall-thickness subsequent to the sizing operation performed thereon.

According to heretofore well-known methods of shaping and sizing the terminal members of pipe fittings, pipes, etc., of the type designed to be telescopically interfitted and united together by means of sweat-soldering operations, the pipe fitting is arranged in a two-part holding-block 35 having complementary cavities formed in the respective members of said holding-block to receive the terminal portion of a pipe-fitting blank and wherein said terminal portion of the pipe-fitting 40 blank is sized and interiorly-shaped by a single cold-working expansion of the unsized terminal of a pipe fitting by a mandrel of predetermined diameter greater than that of the interior surface of the unsized terminal. This method of 45 procedure has produced results that are not entirely satisfactory due largely to certain inherent imperfections and undesirable conditions in the unsized pipe fitting constructed in the usual manner, causing variations in wall-thickness and 50 texture of the metal in the sized pipe fittings.

Efforts have been made to overcome these drawbacks by resorting to reaming operations performed on the terminal-portion of the unsized pipe fitting with a view to rendering the wall- 55

thicknesses as uniform as possible before the said terminal-portions were subjected to the expanding or sizing operations by forcibly inserting thereinto a mandrel of predetermined size 5 or diameter corresponding to that of the interior surface of the sized terminals. The intended purpose of this procedure was to equalize the strains within the metal in such a way as to prevent the sized terminal from going "out of round" 10 after the expanding operation performed on the unsized pipe-fitting terminal. Due to the lack of uniformity in the effects produced by these reaming and similar operations upon the unsized pipe-fitting terminals, the walls of which were 15 non-uniform thickness, efforts in this direction were not entirely successful since a sizing operation performed on an unsized pipe-fitting terminal of the usual form, tends to produce unequalized strains in the metal walls of the sized 20 terminals with a consequential tendency for the sized terminals to spring "out of round" after the sizing operations.

According to my co-pending application Serial No. 146,449 which was filed in the U. S. Patent 25 Office on June 4, 1937, now patent No. 2,174,967 the terminal-portion of an unsized pipe fitting is subjected to two successive cold-working operations, one of which consists in forcibly inserting into an unsized terminal of a pipe fitting a 30 mandrel of predetermined diameter larger than that of the interior surface of said terminal and the second of which consists in ironing-out the exterior surface of said terminal on the said mandrel by a constricting draw-die of predetermined 35 diameter less than that of the exterior surface of said terminal after it is expanded. For this purpose, the body-portion of an unsized pipe fitting is clamped in a holder comprising separable clamping-blocks, the sizing-mandrel 40 being forcibly inserted into the unsized terminal in a direction towards the body-portion of the pipe fitting. This sizing operation is followed by a longitudinal movement of the draw-die member over the normally-stationary exterior wall of the 45 expanded terminal to produce a cold-flowage of the metal away from the body-portion of the pipe fitting on the sizing-mandrel.

According to the present invention, analogous effects on the tubular wall of an unsized pipe fitting, are produced in a simpler and more effective manner in two successive stages, during the former of which a mandrel of predetermined diameter larger than that of the interior surface of an unsized terminal, as well as slightly over-sized with respect to the sized interior of the 55 finished terminal is forcibly inserted into the unsized terminal of the pipe fitting preparatory to the next operating stage. For this primary stage, a pipe-fitting holder of somewhat similar character to that shown and described in my above-identified co-pending application may be employed. After the completion of this primary cold-working operation, the pipe fitting with its oversized terminal is removed from the pipe-fitting 60 holder and positioned in a pipe-fitting holder or draw-die support of peculiar construction to be hereinafter described. Mounted in the pipe-fitting holder or draw-die support, is a normally-stationary ring-shaped draw-die which is suitably 65 constructed to receive the oversized pipe-fitting terminal positioned above and supported by an annular draw-die ledge of the draw-die which, during the secondary stage of the cold-drawing operation, exercises a double function 70 in cooperation with a mandrel of predetermined 75

diameter less than that of the interior diameter of the oversized terminal and which is inserted into the oversized terminal in accurate coaxial relationship to the annular draw-die. Subsequently, this mandrel is forced downwardly 5 through the said draw-die to drive the said terminal through and past the draw-die to effect an ironing operation on the exterior surface of the terminal on the sized mandrel. The effects of this operation are manifold in that it sizes the 10 oversized terminal; reduces the thickness of the terminal wall; reduces the outside diameter of the terminal and renders it more truly cylindrical; improves the texture and tenacity of the metal; and tends to equalize the strains produced 15 in the unsized pipe fitting during its formation. As a direct result, the inner or sized surface of the terminal may be interfitted to within a refined degree of tolerance with pipes, other pipe fittings, and the like, to be connected thereto by 20 means of sweat-soldering or the like.

The particular apparatus illustrated in Figs. 1 to 3 inclusive is designed primarily for expanding the terminals of wrought-metal pipe fittings into bellmouthed form for the telescopic reception of pipes, tubes, or terminals of other pipe fittings. The said apparatus includes a carrier-block or member 20 connected to the gate or ram of a power-press (not shown), a sizing-mandrel 21 being shown depending from the under-side of the said carrier-block or member 20 and provided with a terminal or pilot-nose portion 22. The said mandrel is of predetermined diameter larger than that of the inner surface of the unsized pipe-fitting terminal into 35 which it is to be forcibly inserted.

Arranged below the sizing-mandrel 21 is a pipe-holder which is generally designated by the reference character 23, said fitting-holder being suitably constructed to rest upon the upper surface of the bed of the power-press (not shown). In the form shown in Figs. 1, 2 and 3, the fitting-holder comprises two opposed separable holder-blocks 24-24, each of which is suitably recessed to jointly accommodate a wrought-metal T, such as that designated generally by the reference character 25. The complementary members or holder-blocks 24-24 of the fitting-holder 23, may be firmly held together by any suitable means, such, for example, as plungers 26-26 in Fig. 1. 40

The pipe fitting 25, shown in the form of a T in Figs. 1 to 3, is provided with an unsized branch-terminal 27 which, for the primary stage of the sizing operation, is arranged in a cylindrical portion 28 of the T-shaped recess formed between the opposed holder-blocks 24-24, said branch-terminal being arranged on a vertical axis and in coaxial alignment with the sizing-mandrel 21. During the downward movement of the carrier-block or member 20, the pilot-nose 22 of the 45 sizing-mandrel 21 enters the upper end of the branch-terminal 27 (one of three similar terminals of the T) and guides the said mandrel 21 thereinto to produce an expansion of the branch-terminal 27 within a cylindrical recess 50 28 formed in the holder-blocks 24-24, jointly. Extending around the mandrel and arranged intermediately of the portions 21 and 22 thereof, is a sloping expanding-shoulder 29 which progressively expands the branch-terminal 27 as the said 55 mandrel is forcibly inserted thereinto. Formed jointly in the complementary holder-blocks 24-24, is a shoulder 30 which extends around the recess 28 at the bottom thereof and in the bottommost position of the oversized mandrel 21, 70 75

cooperates with the sloping expanding shoulder 29 to form an outward bulge in the terminal 21 which constitutes the lower border of the oversized bellmouthed form 27a of the terminal, as shown in Fig. 3.

After the remaining two line-terminals of the T 25 have been expanded to an oversize in the foregoing manner, the said terminals are positioned one at a time in a pipe-fitting housing or draw-die support of peculiar form shown in Figs. 4 to 7 inclusive and designated generally by the reference character 31. The said housing or support 31 comprises complementary parts or portions 32—32 opposed each to the other and held together by any suitable means such, for example, as the plungers 33—33 shown in Fig. 6. Mounted in the top wall of the housing or support 31 is a ring-shaped draw-die 34 comprising semicircular sections 34a—34a, said sections being secured in position by means of suitable screws 35. The said draw-die 34 is provided with an inner peripheral wall 36 of sufficient size to permit the coaxial alignment of each oversized bellmouthed terminal 27a of the T 25 placed therein, with respect to an annular draw-die ledge 37 of the ring-shaped draw-die 34, by means of a terminal-sizing-and-moving mandrel to be presently described. The annular draw-die ledge 37 is of predetermined diameter less than that of the outer surface of the oversized-terminal 27a of the pipe fitting 25 when the same is expanded, and is suitably constructed to supportably engage the inner edge of the said oversized bellmouthed terminal. The housing or support 31 is suitably constructed to be placed upon the bed-plate (not shown) of a power-press and when properly located on the said bed-plate in position to support the annular draw-die ledge 37 in accurate coaxial alignment with the longitudinal axis of a reciprocatory terminal-sizing and pipe-fitting-actuating mandrel operated by the power-press in the manner to be presently described. The said power-press may include a carrier-block or member 38 to which is secured the upper end of a sizing-mandrel 39 of predetermined diameter slightly less than that of the interior diameter of the oversized bellmouthed terminal 27a. The said sizing-mandrel is provided at its lower end with a pilot-portion 40 and a shoulder-portion 41 which operate to centralize the terminal with respect to the mandrel 39 as the said pilot 40 moves downwardly through said terminal.

The sizing-mandrel 39 is preferably constructed of tool-steel, carefully ground to size around its exterior surface to adapt it to perform an accurate sizing operation upon the interior surface of the bellmouthed terminal 27a or other similar terminal when the same is forcibly driven downwardly through and past the annular draw-die ledge 37 so that when the sized terminal is interfitting with another pipe fitting, pipe, or the like, an interfitting connection with a refined degree of tolerance may be formed between the joint-forming walls to insure the necessary capillarity between the surfaces to be joined by means of sweat-soldering.

It will be understood from the foregoing description that as the sizing-mandrel 39 is forcibly moved downwardly into the bellmouthed terminal 27a within the ring-shaped draw-die 34 and in accurate coaxial alignment with the annular draw-die ledge 37 of predetermined diameter, the said terminal 27a will be positioned by means of the sizing-mandrel 39 with its slightly-oversized interior surface substantially in coaxial align-

ment with the common axis of the mandrel 39 and the annular draw-die ledge 37. Under these conditions, as the terminal 27a is driven downwardly by the mandrel 39 through and past the annular draw-die ledge 37, the exterior surface of the expanded terminal will be ironed out or compressed upon the sizing-mandrel 39 to accurately size the interior surface of the terminal; to reduce the thickness of the terminal wall; and to provide the terminal with an outer surface which is more truly cylindrical. As shown in Fig. 5, the joint movement of the sizing-mandrel and terminal through the annular draw-die ledge 37 operates to fasten the said terminal to the sizing-mandrel 39 with a close frictional grip by means of which the pipe fitting is suspended after the terminal has become disengaged from the annular draw-die ledge 37. As the mandrel 39 moves upwardly in preparation for another operation, the pipe-fitting T 25 is stripped or detached therefrom by the engagement of the latter with the under-surface of the draw-die ledge 37.

It will be understood from the foregoing description that the pipe-fitting T is completed by a repetition of the shaping and sizing operation described above, on both of the terminals of the main body- or run-portion thereof. As shown diagrammatically in Fig. 8, the above-described operation performed on each of the plain terminals 27 of an unsized pipe-fitting 25 produces first an oversized bellmouthed terminal 27a shown in dotted lines in Fig. 8, and then a reduced shaping and sizing of the said oversized bell-mouthed terminal 27a to produce a pipe-fitting T having a reduced bellmouthed terminal 27b as shown in Fig. 9.

Figs. 10 to 14 inclusive show suitable apparatus for producing elbows in accordance with the present invention, said elbows being provided with bellmouthed terminals having the improved qualities inherent in the bellmouthed terminals formed in the above-described manner. For this purpose, a pipe-fitting housing and draw-die support designated generally by the reference character 43 is provided, wherein a continuing downward movement of an elbow, designated generally by the reference character 48, is accommodated during a shaping and sizing operation conducted on a preexpanded slightly-oversized terminal of the elbow.

In the form shown, the pipe-fitting housing and draw-die support 43 comprises oppositely-arranged complementary sections or members 44—44 which may be held together in any suitable manner such, for example, as by means of coaxially-arranged plungers such as those shown at 26—26, in Fig. 1. Mounted in the top-wall of the housing 43, is a two-part ring-shaped draw-die 45 preferably constructed in separable sections to correspond with the parting-plane of the sections 44—44 of the housing 43. The two-part ring-shaped draw-die 45 is provided at its bottom-end with an annular draw-die ledge designated by the reference character 46 and preferably constructed in two semicircular sections 63 separable in the parting-plane of the sections 44—44 of the housing 43 to permit the positioning therein, by a lateral movement, of a preexpanded slightly-oversized terminal 47 of an elbow. It will be understood, in this connection, that the elbow 48 shown in Figs. 10 to 13 inclusive, is provided at its respective opposite ends respectively with slightly-oversized terminals 47 and 50 which have been preexpanded and preformed substantially in the same manner as that employed in the forma-

tion of the bellmouthed terminal 27a of the pipe-fitting T 25, as shown in Figs. 1 to 3. It will be understood, furthermore, that the annular draw-die ledge 46 is of predetermined diameter less than that of the exterior surface of the bell-mouthed terminals 47 and 50 with which the elbow 48 has been preformed. The split ring-shaped draw-die 45 may be retained in position in the top-wall of the housing 43 by means of 10 screws 49.

The oversized terminal 50 of the elbow 48 is first mounted upon a cylindrical head 51 of predetermined diameter fitting the interior surface of the said terminal 50, after which the complementary terminal 47 is brought into position within the upper portion of the draw-die 45, the respective halves of which are brought together concurrently with the clamping together of the sections 44-44 of the housing 43.

20 The cylindrical head 51 is provided with a threaded stem 52 mounted in a sleeve 53, which latter is slidably mounted in a vertical slot 54 formed half in each of the abutting sections 44-44 of the housing 43 and symmetrically disposed with respect to the parting-plane between said housing sections. For the purpose of constraining the slightly-oversized terminal 47 of the 25 90° elbow 48 to an axial path coincident with the common axis of the annular draw-die ledge 46 and a sizing-mandrel 63 to be hereinafter described, during a continued downward movement of the said mandrel and terminal through and past the said annular draw-die ledge 46, the present invention contemplates suitable means 30 for maintaining the longitudinal axis of the threaded stem 52 and the cylindrical head 51 perpendicular to the vertical axis common to the annular draw-die ledge 46 and the sizing-mandrel 63. For this purpose and in the form shown 35 in the drawings, a plate 55 is threaded onto the stem 52 and is provided with a finished surface in slidable engagement with finished guide-surfaces 56-56 extending parallel with and on each of the respective opposite sides of the vertical slot 54. The disk-like plate 55 is provided with a retaining-rib 57 which slides in a vertical groove 58 formed in the inner face 56 in the adjacent end-wall of the housing 43 (Fig. 12) whereby the unit compressing the stem 52 and the parts thereon, is movably organized with one of the sections 44 of the housing 43, to thus maintain the said unit in place when the sections 44-44 are separated during the removal or insertion of a fitting therebetween.

45 For the purpose of retaining the disk-like plate 55 in slidable abutment with the surfaces 56-56 during the vertical movement of the former, a second disk-like plate 59 is threaded onto the outer portion of the threaded stem 52 to slidably contact with finished guide-surfaces 56a-56a extending along the outer margin of the vertical groove 54. Threaded to the outer end of stem 52 is a lock-nut 60 which is adapted to secure the plates 55 and 59 in abutment with opposite ends of the sleeve 53 after the cylindrical head 51 has been axially adjusted in proper supporting position with respect to the terminal 50 of the elbow 48. For the purpose of axially adjusting the cylindrical head 51 within the terminal 50, an outer reduced end-portion 61 of threaded stem 52 is provided with a kerf 62 to receive a screw driver.

50 It will now be understood from the foregoing description that after an elbow 48 has been correctly positioned within the housing 43, a down-

ward displacement of the slightly-oversized terminal 47 of the elbow through and past the annular draw-die ledge 46, will be constrained to a path coincident with the axis of the said annular draw-die ledge. The housing 43 is constructed to 5 be placed upon the bed-plate (not shown) of a power-press which includes means of suitable construction for moving the sizing-mandrel 63 in a path perpendicular to the bed of the said power-press.

10 With the elbow 48 properly positioned in the housing 43 in the manner described above, the said housing 43 is arranged in a predetermined position on the bed-plate of the power-press with the sizing-mandrel 63 in coaxial alignment with the vertical axis of the annular draw-die ledge 46. A pilot 64 at the bottom end of the sizing-mandrel 63 is formed of suitable size and shape to enter the unexpanded portion of the elbow immediately below the oversized terminal-portion 47 thereof. When the said pilot 64 is lowered into engagement with the inner wall of the unexpanded portion of the elbow 48, a sloping thrust-shoulder 65 located between the pilot 64 and the main body of the sizing-mandrel 63, is brought into engagement with the inner wall of the terminal 47 at its lower end. With the several parts thus arranged, the downward movement of the sizing-mandrel 63 is continued and imparts downward movement to the terminal 47 through and past the annular draw-die ledge 46, the said downward movement being terminated after the upper edge of the terminal 47 of the elbow 48 has been moved below the annular draw-die ledge 46 to a position indicated in dotted lines in Fig. 11.

20 As the elbow 48 is forced bodily downward as just above described, the guide-unit comprising the head 51 and the parts organized therewith, serves to maintain the axes of the two terminals 47 and 50 at a predetermined angular relationship, i. e., 90° in the instance shown. The guide-unit just referred to also constrains the bodily movement of the elbow to a path parallel with the axis of the mandrel 63.

25 It will now be readily understood from the foregoing description that due to the arrangement of the annular draw-die ledge 46 in a normally-stationary position, in which it is rigidly held in coaxial relationship with respect to the reciprocating sizing-mandrel 63, the slightly-oversized terminal 47 of elbow 48 will be forcibly driven through and past the draw-die ledge 46 during a continued joint movement of the sizing-mandrel 63 and the said terminal 47. The interior surface of the oversized terminal 47 will thus be forced into close frictional engagement with the exterior surface of the sizing-mandrel 63 at the same time that it is accurately sized exteriorly by being bodily forced past the said annular draw-die ledge 46. In this manner, the 30 exterior surface of the terminal 47 will be ironed out into true cylindrical form and its tubular wall will be reduced in thickness.

35 As shown diagrammatically in Fig. 13, the above-described shaping and sizing operation in a general way converts the relatively-large oversize and somewhat-irregular terminal 47 to a relatively-smaller sized terminal 47a having exterior and interior surfaces that are rendered cylindrical to a more refined degree. During this conversion in form, the hardness, tenacity and texture of the metal is greatly improved by a condensation and cold-flowage of the metal longitudinally of the terminal during the radial con-

traction of the terminal to its final size and shape.

The invention may be carried out in other specific ways than those herein set forth, without departing from the spirit and essential characteristics of the invention, and the present embodiments are, therefore, to be considered in all respects as illustrative and not restrictive, and all changes coming within the meaning and 10 equivalency range of the appended claims are intended to be embraced therein.

I claim:

1. A method of sizing pipe-fitting terminals, comprising: forcibly inserting into an unsized terminal of a pipe fitting, a mandrel of predetermined diameter larger than that of the interior surface of the said terminal; in removing the said mandrel from the terminal thus expanded; in inserting into the said terminal thus expanded another mandrel of predetermined diameter slightly less than the diameter of the first-mentioned mandrel; and in ironing out the exterior surface of said terminal on the second-mentioned mandrel by a constricting draw-die of predetermined diameter less than that of the exterior surface of the terminal after it is expanded.

2. A method of sizing pipe-fitting terminals, comprising: forcibly inserting into an unsized terminal of a pipe fitting, a mandrel of predetermined diameter larger than that of the interior surface of said terminal; removing the said mandrel from the terminal thus expanded; inserting into the said terminal thus expanded another mandrel of predetermined diameter slightly less than the diameter of the first-mentioned mandrel; and in ironing out the exterior surface of said terminal on the second-mentioned mandrel by a constricting draw-die of predetermined diameter less than that of the exterior surface of said terminal after it is expanded, the said draw-die having a working surface substantially similar in shape to that of the second-mentioned mandrel; the second-mentioned mandrel and draw-die being held in coaxial relationship during the ironing operation.

3. A method of sizing pipe-fitting terminals,

comprising: forcibly inserting into an unsized terminal of a pipe fitting, a mandrel of predetermined diameter larger than that of the interior surface of the said terminal and slightly larger than that of the interior surface of the sized terminal to be formed from the expanded terminal; in removing the terminal thus expanded from the said mandrel; in inserting into the said expanded terminal another mandrel of predetermined diameter substantially equal to that of the 10 sized interior surface of the sized terminal; and ironing out the exterior surface of the expanded terminal on the second-mentioned mandrel by a 15 constricting draw-die of predetermined diameter less than that of the exterior surface of the terminal after its expansion on the first-mentioned mandrel whereby the said interior surface of the expanded terminal is reduced to size.

4. A method of producing a sized bellmouthed pipe-fitting terminal, including: introducing into 20 an unsized terminal-portion of a pipe fitting, an oversized mandrel of predetermined diameter slightly larger than that of the inner surface of the finished bellmouthed terminal to be formed on the pipe fitting; removing the oversized bellmouthed terminal from the said mandrel; placing a neck-portion of the pipe fitting at the inner end of the oversized bellmouthed terminal in one portion of a split-ring-shaped draw-die of 25 predetermined diameter slightly less than that of the exterior surface of the oversized terminal; placing a complementary portion of the said draw-die in assembled position with respect to the first said portion; inserting into the said terminal a sizing-mandrel of predetermined diameter 30 slightly less than that of the inner surface of the oversized terminal and substantially the same as that of the inner surface of the finished bellmouthed terminal; and in forcibly moving the last-mentioned mandrel with the said 35 terminal through and past the said ring-shaped draw-die to effect a cold-working of the oversized terminal on the last-mentioned mandrel and a sizing of the inner surface of the said terminal.

EUGENE M. CARTWRIGHT.
